TYPOGRAPHICAL COMPOSING AND
CASTING MACHINE

Hermann Brandenburg, Berlin-Tempelhof, Germany, assignor to Mergenthaler Linotype Company, Brooklyn, N. Y., a company of New York

Application November 2, 1939, Serial No. 302,519
In Germany October 27, 1938

20 Claims. (Cl. 199—51)

This invention relates to typographical composing and casting machines, wherein matrices and spacebands are assembled in line and the composed line presented to a mold for the casting of a slug or type-bar, and wherein prior to casting, the spacebands are expanded by a so-called justification bar to justify the line. The movement of the justification bar is controlled by a spring in conjunction with a cam mounted on the main cam shaft of the machine. The composed lines contain a varying number of spacebands according to the number of words in a line and the length of the line, but the force exerted by the spring and justification bar against the spacebands is always the same. Consequently, the force which is individually applied to each spaceband is very much reduced when there are a large number of spacebands in the line. The result is that when there are only a few spacebands in the line, too much force is applied so that the spacebands may become damaged. On the other hand when a large number of spacebands are present in the line, the force applied is not always sufficient to effect proper justification.

It has already been proposed to provide means, controlled by a hand or foot lever, for adjusting the tension of the spring acting upon the justification bar. Such an adjustment however, can only be made in accordance with the length of the line as it is obviously not practicable for the operator to count the number of spacebands assembled in every line and then to adjust the spring to a tension appropriate to the said number. Moreover, the adjustment of the tension of the spring according to the line length is not effective for the purpose of eliminating the aforesaid disadvantages, because the number of spacebands used is not dependent upon the length of the line.

The object of the invention is to provide means whereby a uniform justifying pressure upon the spacebands individually will be applied irrespective of the number of spacebands contained in the line, so that on the one hand, proper justification will be secured, and on the other hand, an excessive justifying pressure upon each spaceband will be avoided. For this purpose, according to the invention, the adjustment according to the number of spacebands present in the line is effected automatically by the spaceband releasing means.

In the drawing, one constructional form of the invention is illustrated, and in the said drawing: 55 Figure 1 is a diagrammatical representation

of the parts of a matrix composing and line-casting machine pertinent to the present invention; and

Figures 2 to 4 show a regulator valve in respectively different positions of adjustment. 5

The matrix line 1 is held in the known manner in the vise frame of the machine between two clamping jaws 2 and 3 adjusted to the line length, there being spacebands 4 between the words in the line. For justifying the line, the justification bar 5 is driven upwardly against the spacebands. The release of the spacebands from a magazine which is not shown in the drawing is effected in a known manner by the spaceband key 6 which rocks about the pivot 7 when the key is depressed to move upwardly an escapement reed 8 mounted upon its rear end, which in turn effects in known manner the release of the spacebands which drop into the line. In the constructional form of apparatus according to the invention illustrated in the drawing the escapement reed 8 is provided with a contact piece 9, which, when the reed is elevated, that is, when a spaceband is released, connects with a contact 10. Thereby an electrical circuit is closed and current flows from any preferred source of electrical energy 11 along the lead 12, across the contacts 10 and 9, along the lead 13, through a solenoid 14, and along the lead 12 to the source 11. 10 15 20 25 30

The justification bar 5 is mounted on a piston rod 15 which is connected to a piston 17 in a cylinder 16. The lower end of the cylinder 17 is connected to a pipe 18, the other end of which connects with the upper part of a cylinder 35 19. In the cylinder 19 is a plunger 20 which is connected by a link 21 to one arm 22 of a two-armed lever, which swings about a pivot 23. At the end of the second arm 24 of the two-armed lever, there is a roller 25 which bears on 40 the edge of a cam 27 mounted on the main cam shaft 26 of the machine. A spring 28 fast at one end to the machine frame, and attached at the other end to the lever arm 24, holds the roller 25 in contact with the cam 27 and rocks 45 the lever 22, 24 clockwise when so allowed by the cam 27.

Upon the cylinder 19 is mounted a fluid container 29, which is connected to the cylinder 19 by means of a non-return valve 30. Fluid may 50 therefore pass by suction from the container 29, into the cylinder 19, but not in the reverse direction, that is to say, no fluid can be forced from the cylinder 19 into the container 29.

An opening 31 leading into the cylinder 19 55

communicates with a second pipe 32 connected to the cylinder by means of a non-return valve 33 through which fluid may enter the pipe 32 from the cylinder 19, but may not flow in the reverse direction. The pipe 32 leads into the interior of a rotatable valve 34, which is in the form of a hollow cylinder closed at one end. This valve is mounted upon a shaft 35, and has a slot 36 formed in a part of its periphery located opposite a recess 37 in the valve casing. To this recess is connected a pipe 38 leading to the container 29.

Loosely mounted on the shaft 35 of the valve 34 is a ratchet wheel 39 with which two pawls 40 and 41 engage. The pawl 40 is mounted on a fixed pivot, and is held in engagement with the ratchet wheel by a spring (not shown) so as to prevent backward turning of the ratchet wheel. The pawl 41 is pivotally mounted on a stud 42, and is held in engagement with the ratchet wheel by a spring (not shown). The stud 42 is fast to an arm 43 pivotally mounted on the shaft 35, and the said arm is connected to the core piece of the solenoid 14 by a link 44.

Secured to the ratchet wheel 39 is a coupling disc 45 with which engages a clutch member 46, which is slidable on the shaft 35 but rotatable therewith. The clutch is controlled by the forked end of a two-armed lever 47 which is capable of being rocked about the pivot 23 and carries at the end of its second arm a roller 48 bearing on a cam disc 49, mounted on the main cam shaft 26 of the machine.

The operation of the above-described mechanism is as follows:

When a spaceband is released, the contacts 9, 10 are closed, thus allowing the solenoid 14 to become energised and the core piece thereof to be raised.

Consequently, the arm 43 with the pawl 41 is rocked for a certain distance, for instance to an extent sufficient to turn the ratchet wheel 39 by one tooth. Ordinarily, the clutch 45, 46 is engaged and remains in engagement so long as the roller 48 bears on the curved surface of the cam disc 49. Therefore, the ratchet wheel 39, which is loosely mounted on the shaft 35, but is coupled to it through the clutch 45, 46, rotates the valve 34, so as gradually to bring the slot 36 out of communication with the recess 37.

Figure 2 shows the position of the valve 34 when the composition of a line is begun. It will be seen that in this position the full length of the slot 36 communicates with the recess 37. Figure 3 shows the position of the valve 34 after a few spacebands have been released and assembled. It will be noticed that here a portion only of the slot 36 communicates with the recess 37. Figure 4 finally shows the position of the valve 34 after a maximum number of spacebands has been assembled, and where there is no longer any communication between the interior of the valve 34, and the recess 37 or the pipe 38 connected therewith.

When the composition of the line is completed and the valve 34, through spaceband release, has assumed a position corresponding to a certain number of spacebands, the line is transferred to the first elevator, and justification takes place. The cam 27 by reason of its special contour rocks the lever 22, 24 in an anti-clockwise direction, so pushing the plunger 20 into the cylinder 19, and causing the fluid, preferably oil, in the cylinder 19 to flow through the pipe 18, into the cylinder

16 to raise the piston 17, and move the justification bar 5 against the spacebands 4.

The force with which the piston 17 is moved upwardly, that is, the force expended on justification, depends upon the resistance which the pipe 32 or the valve 34 connected to the said pipe, offers to the flowing out of the fluid from the cylinder 19. This resistance in turn is dependent on the position of the slot 36, that is to say the number of spacebands present in the line. Thus the force expended on justification will be automatically regulated in accordance with the number of spacebands present in the line.

The compressed fluid passing through the slot 36 is returned to the container 29 through the pipe 38, and the plunger 20 at its subsequent downward stroke draws out of the container 29 the fluid previously injected through the pipes 32, 38.

The cam 27, as is well known, is constructed so that a two-stage justification movement takes place, that is to say, the justification bar 5 is lowered after the first upward movement and is again moved upwardly against the spacebands.

When justification has been completed the cam piece 50 of the cam disc 49 comes into contact with the roller 48, thus rocking the lever 47 in a clockwise direction and disengaging the clutch 46. The valve 34 is thus disconnected from the ratchet wheel 39 and is returned to the initial position shown in Figure 2 by means of a spring 52 connected to an arm 51 fixed to the shaft 35. In the said initial position the arm 51 rests against a stop 53.

In the above described construction, justification is effected by hydraulic or pneumatic means. Obviously, mechanical or electrical means can be provided for moving the justification bar in which case, the electrical or mechanical force imparted to the justification bar must be adjusted in accordance with the number of spacebands which have been assembled.

The pump cylinder 19 must be made of such a size larger than the cylinder 16, that notwithstanding the compressed fluid in the branch pipe 32, the justification bar will in every case be raised to its uppermost position.

Having described my invention, I declare that what I claim and desire to secure by Letters Patent is:

1. In a typographical composing and casting machine, the combination with means for releasing spacebands from a magazine to be assembled with a line of matrices and means for justifying the line of matrices and spacebands, said justifying means including a driving member common to all the spacebands in the line, of means controlled according to the number of spacebands in the line adapted automatically to vary the force applied to said driving member.

2. In a typographical composing and casting machine, the combination with means for releasing spacebands from a magazine to be assembled with a line of matrices and means for justifying the line of matrices and spacebands, of means controlled directly by the spaceband releasing means adapted to adjust the force applied to the justifying means in accordance with the number of spacebands in the line.

3. In a typographical composing and casting machine, the combination with a spaceband key and escapement reed for releasing spacebands from a magazine to be assembled with a line of matrices and means for justifying the line of matrices and spacebands, of setting mechanism

adapted to be operated at each releasing movement of the spaceband escapement reed, and means controlled by said setting mechanism adapted automatically to adjust the force applied to the justifying means according to the number of spacebands in the line.

4. In a typographical composing and casting machine, the combination with a spaceband key and escapement reed for releasing spacebands

10 from a magazine to be assembled with a line of matrices and means for justifying the line of matrices and spacebands of a solenoid adapted to be energised at each releasing movement of the spaceband escapement reed, pawl and ratchet mechanism, adapted to be operated by said solenoid, and means controlled by said pawl and ratchet mechanism adapted automatically to adjust the force applied to the justifying means according to the number of spacebands in the line.

20 5. In a typographical composing and casting machine, the combination with means for releasing spacebands from a magazine to be assembled with a line of matrices and means for justifying the line of matrices and spacebands, 25 of hydraulic means controlled directly by the spaceband releasing means adapted to adjust the force applied to the justifying means in accordance with the number of spacebands in the line.

6. In a typographical composing and casting 30 machine, the combination with means for releasing spacebands from a magazine to be assembled with a line of matrices and means for justifying the line of matrices and spacebands, of a rotary valve adapted to be turned at each 35 operation of the spaceband releasing means, a hydraulic system connected to said valve wherein the pressure is varied according to the position to which the valve has been turned, and means whereby the hydraulic system controls the 40 force imparted to the justifying means.

7. In a typographical composing and casting machine, the combination with means for releasing spacebands from a magazine to be assembled with a line of matrices of a justification 45 bar adapted to be operated by hydraulic means to justify a line of matrices and spacebands, a rotary valve adapted to be turned at each operation of the spaceband releasing means and a hydraulic system wherein the pressure is varied 50 according to the position to which the valve has been turned connected between said valve and justification bar so that the force applied to move the justification bar is automatically adjusted according to the number of spacebands 55 in the line.

8. In a typographical composing and casting machine, the combination with means for releasing spacebands from a magazine to be assembled with a line of matrices, of a justification bar connected to a piston in a cylinder to which fluid is supplied under pressure, a rotary valve adapted to be turned at each operation of the spaceband releasing means, and a pump for supplying fluid under pressure to said piston and cylinder and to said valve so that the pressure of the fluid supplied to the piston and cylinder is varied according to the position to which the valve has been turned.

9. In a typographical composing and casting 70 machine, the combination with means for releasing spacebands from a magazine to be assembled with a line of matrices, of a justification bar connected to a piston in a cylinder to which fluid is supplied under pressure, a rotary valve adapted to be turned at each operation of the

spaceband releasing means, a pump for supplying fluid under pressure to said piston and cylinder, a container for supplying fluid to said pump, and a circulatory system for fluid under pressure extending between said pump, rotary valve and container so that a variation in the position of the rotary valve effects a variation in the pressure of fluid supplied to said piston and cylinder.

10. In a typographical composing and casting 10 machine, the combination with means for releasing spacebands from a magazine to be assembled with a line of matrices, of a justification bar connected to a piston in a cylinder to which fluid is supplied under pressure, a hollow rotary 15 valve adapted to be turned at each operation of the spaceband releasing means, a casing for said valve with a fluid supply inlet communicating with the interior of the hollow valve, a slot in the valve communicating with an outlet recess in said casing, a pump for supplying fluid under pressure to said piston and cylinder, a container for supplying fluid to said pump, a pipe for supplying fluid under pressure from the pump to the inlet of the rotary valve, a valve in said pipe for preventing reversal of the flow of fluid in said pipe, an outlet pipe connected between the outlet recess in the valve casing and the fluid container, and a valve in the container through 20 which fluid is drawn into the pump cylinder.

11. In a typographical composing and casting machine, the combination with means for releasing spacebands from a magazine to be assembled with a line of matrices, of a justification bar connected to a piston in a cylinder to which fluid is supplied under pressure, a hollow rotary valve, a rotatable shaft on which said valve is mounted, driving means adapted to turn said shaft at each operation of the spaceband releasing means, clutch mechanism on said shaft 40 adapted to connect and disconnect the rotary valve to and from the driving means at each cycle of operations of the machine, a spring for returning said shaft and valve to an initial position, a casing for said valve with a fluid supply inlet communicating with the interior of the hollow valve, a slot in the valve communicating with an outlet recess in said casing, a pump for supplying fluid under pressure to said piston and cylinder, a container for supplying fluid to 50 said pump, a pipe for supplying fluid under pressure from the pump to the inlet of the rotary valve, a valve in said pipe for preventing reversal of the flow of fluid in said pipe, an outlet pipe connected between the outlet recess in the valve 55 casing and the fluid container, and a valve in the container through which fluid is drawn into the pump cylinder.

12. In a typographical composing and casting machine, the combination with a spaceband key and escapement reed for releasing spacebands from a magazine to be assembled with a line of matrices and means for justifying the line of matrices and spacebands, of setting mechanism adapted to be operated at each releasing movement of the spaceband escapement reed, a rotary valve adapted to be operated by said setting mechanism, a hydraulic system connected to said valve wherein the pressure is carried according to the position to which the valve has 70 been turned, and means whereby the hydraulic system controls the force imparted to the justifying means.

13. In a typographical composing and casting machine, the combination with a spaceband key 75

- and escapement reed for releasing spacebands from a magazine to be assembled with a line of matrices and means for justifying the line of matrices and spacebands, of a solenoid adapted 5 to be energised at each releasing movement of the spaceband escapement reed, pawl and ratchet mechanism, adapted to be operated by said solenoid, a rotary valve adapted to be turned at each operation of said pawl and ratchet mechanism, and means adapted to vary the pressure of a hydraulic system according to the position to which the valve has been turned connected between said valve and justification means so that the force applied to operate the justification means is automatically adjusted according to the number of spacebands in the line.
14. In a typographical composing and casting machine, the combination of a spaceband key and escapement reed for releasing spacebands 10 from a magazine to be assembled with a line of matrices, means for justifying the line of matrices and spacebands comprising a justification bar connected to a piston in a cylinder to which fluid is supplied under pressure, a solenoid adapted to be energised at each releasing movement of the spaceband escapement reed, pawl and ratchet mechanism adapted to be operated by said solenoid, a rotary valve adapted to be turned at each operation of the pawl and ratchet mechanism, and a pump for supplying fluid under pressure to said piston and cylinder and to said valve so that the pressure of the fluid supplied to the piston and cylinder is varied according to the position to which the valve has been turned.
15. In a typographical composing and casting machine, the combination of a spaceband key and escapement reed for releasing spacebands 15 from a magazine to be assembled with a line of matrices, means for justifying the line of matrices and spacebands comprising a justification bar connected to a piston in a cylinder to which fluid is supplied under pressure, a solenoid adapted to be energised at each releasing movement of the spaceband escapement reed, pawl and ratchet mechanism adapted to be operated by said solenoid, a hollow rotary valve, a rotatable shaft on which said valve is mounted, clutch mechanism on said shaft adapted to connect and disconnect the rotary valve to and from the pawl and ratchet mechanism at each cycle of operations of the machine, a spring for returning said shaft and valve to an initial position, a casing for said valve with a fluid supply inlet communicating with the interior of the hollow valve, a slot in the valve communicating with an outlet recess in said casing, a pump for supplying fluid under pressure to said piston and cylinder, a container for supplying fluid to said pump, a pipe for supplying fluid under pressure from the pump to the inlet of the rotary valve, a valve in said pipe for preventing reversal of the flow of fluid in said pipe, an outlet pipe connected between the outlet recess in the valve casing and the fluid container, and a valve in the container through which fluid 20 is drawn into the pump cylinder.
16. In a typographical composing and casting machine, the combination of a spaceband key and escapement reed for releasing spacebands 25 from a magazine to be assembled with a line of matrices, means for justifying the line of matrices and spacebands comprising a justification bar connected to a piston in a cylinder to which fluid is supplied under pressure, a solenoid adapted to be energised at each releasing movement of the spaceband escapement reed, pawl and ratchet mechanism adapted to be operated by said solenoid, a hollow rotary valve, a rotatable shaft on which said valve is mounted, clutch mechanism on said shaft adapted to connect and disconnect the rotary valve to and from the pawl and ratchet mechanism at each cycle of operations of the machine, a spring for returning said shaft and valve to an initial position, a casing for said valve with a fluid supply inlet communicating with the interior of the hollow valve, a slot in the valve communicating with an outlet recess in said casing, a pump for supplying fluid under pressure to said piston and cylinder, a container for supplying fluid to said pump, a pipe for supplying fluid under pressure from the pump to the inlet of the rotary valve, a valve in said pipe for preventing reversal of the flow of fluid in said pipe, an outlet pipe connected between the outlet recess in the valve casing and the fluid container, and a valve in the container through which fluid 30 is drawn into the pump cylinder.
17. In a typographical composing and casting machine, the combination of a spaceband key and escapement reed for releasing spacebands 35 from a magazine to be assembled with a line of matrices, means for justifying the line of matrices and spacebands comprising a justification bar connected to a piston in a cylinder to which fluid is supplied under pressure, a solenoid adapted to be energised at each releasing movement of the spaceband escapement reed, pawl and ratchet mechanism adapted to be operated by said solenoid, a hollow rotary valve, a rotatable shaft on which said valve is mounted, clutch mechanism on said shaft adapted to connect and disconnect the rotary valve to and from the pawl and ratchet mechanism at each cycle of operations of the machine, a spring for returning said shaft and valve to an initial position, a casing for said valve with a fluid supply inlet communicating with the interior of the hollow valve, a slot in the valve communicating with an outlet recess in said casing, a pump for supplying fluid under pressure to said piston and cylinder, a container for supplying fluid to said pump, a pipe for supplying fluid under pressure from the pump to the inlet of the rotary valve, a valve in said pipe for preventing reversal of the flow of fluid in said pipe, an outlet pipe connected between the outlet recess in the valve casing and the fluid container, and a valve in the container through which fluid 40 is drawn into the pump cylinder.
18. In a typographical composing and casting machine, the combination as in claim 17 wherein the clutch mechanism for connecting and disconnecting the rotary valve to and from the pawl and ratchet mechanism is controlled by a cam on the main cam shaft of the machine.
19. In a typographical composing and casting machine, the combination as in claim 17 wherein the pump for supplying fluid under pressure is controlled by a cam on the main cam shaft of the machine.
20. In a typographical composing and casting machine, the combination as in claim 17 wherein the escapement reed for releasing spacebands carries a contact which on upward movement of the escapement reed, closes an electrical circuit for energising the solenoid for operating the pawl and ratchet mechanism.

HERMANN BRANDENBURG.
